UNITED STATES PATENT OFFICE

153,302

DESIGN FOR A TELESCOPE

John R. Miles, Desplaines, Ill., assignor to Swain Nelson Company, Glenview, Ill., a corporation of Illinois

Application October 25, 1946, Serial No. 134,221

Term of patent 14 years

(Cl. D57—1)

To all whom it may concern:

Be it known that I, John R. Miles, a citizen of the United States, residing at Desplaines, in the county of Cook and State of Illinois, have invented a new, original, and ornamental Design for Telescope, of which the following is a specification, reference being had to the accompanying drawing, forming a part thereof.

The figure is a perspective view of a telescope, showing my new design.

I claim:

The ornamental design for a telescope, substantially as shown.

JOHN R. MILES.
